ORNAMENTAL BORDER FOR GLASSWARE, &c.

No. ^D18,301.

Patented May 8, 1888

UNITED STATES PATENT OFFICE.

THOMAS G. HAWKES, OF CORNING, NEW YORK.

DESIGN FOR AN ORNAMENTAL BORDER FOR GLASSWARE, &c.

SPECIFICATION forming part of Design No. 18,301, dated May 8, 1888.

Application filed March 17, 1888. Serial No. 287,568. Term of patent 7 years.

To all whom it may concern:

Be it known that I, THOMAS G. HAWKES, a citizen of the United States, residing at Corning, in the county of Steuben and State of New York, have invented and produced a new and original Design for a Border for the Ornamentation of Glass and other Ware, of which the following is a specification, reference being had to the accompanying photograph, forming part thereof.

I show my design applied as an ornament to a glass dish; but it may be applied to a goblet, a decanter, or other table glass or ware without regard to the shape of the article.

My design relates to an ornamental border; and my invention consists in an outer series of fan-shaped figures, 2, and an inner series of fan-shaped figures, 3, separated by crossed single cuts 1, forming a series of shields divided by crossed cuts 4, presenting four truncated pyramids, 5 6 7 8, crossed cuts in the pyramids 5 presenting a checkered surface of small truncated pyramids, radial cuts in the pyramids 6, and crossed cuts in the pyramids 7 8.

Having thus described my design, the following is what I claim as new therein and desire to secure by Design Letters Patent:

The design for a border for the ornamentation of glass and other ware herein described and shown, the same consisting of an outer series of fan-shaped figures, an inner series of fan-shaped figures, series of crossed single cuts separating the outer and inner series of fan-shaped figures, forming shields between the series of crossed single cuts, the crossed single cuts extending across the shields, presenting four truncated pyramids, crossed single cuts in the outer and inner pyramids, crossed single cuts in the pyramids on one side of the shields, presenting a checkered surface of small truncated pyramids, and radial cuts in the shields on the other side of the pyramids.

THOMAS G. HAWKES.
